[57] **CLAIM**

The ornamental design for a cage mounted poultry watering unit, substantially as shown and described.

DESCRIPTION

FIG. 1 is a perspective view taken from the top, front and left side of a cage mounted poultry unit showing my new design;

FIG. 2 is a right side elevational view thereof;

FIG. 3 is a front elevational view thereof; and

FIG. 4 is a rear elevational view thereof with the watering cup portion omitted for convenience of illustration.

FIG. 1

FIG. 2

FIG. 3

FIG. 4
